UNITED STATES PATENT OFFICE.

WILLIAM WAERN, OF STOCKHOLM, SWEDEN.

BARK-STRIPPING MACHINE.

1,301,198.

Specification of Letters Patent. Patented Apr. 22, 1919.

Application filed November 22, 1918. Serial No. 263,735.

To all whom it may concern:

Be it known that I, WILLIAM WAERN, engineer, subject of the King of Sweden, residing at 18 Rörstrandsgatan, Stockholm, Sweden, have invented certain new and useful Improvements in Bark-Stripping Machines, of which the following is a specification.

In bark stripping machines having rotating cutter disks the change of cutters has hitherto been connected with difficulties due chiefly to the fact that the fixing and detaching of the cutters had to be effected on the bark stripping machine. The change of cutters, therefore, involved a considerable loss of time and in addition thereto the cutter disk could not readily be properly balanced. These disadvantages are particularly prevailing in such bark stripping machines which are provided with an outer protecting disk and in which the cutter disk is adjustably arranged behind said protecting disk.

According to the present invention said disadvantage is overcome by fastening the protecting disk as well as the cutter disk on different concentric shafts by means of screw-threads running in opposite directions, said disks being so connected with each other that they may be displaced axially but not turned relatively to each other. By this arrangement, when the cutters are to be changed, the protecting disk and the cutter disk may be screwed off from their corresponding shafts simultaneously which is effected by turning both shafts simultaneously in opposite directions. In addition, the advantage is gained that the adjustment of the cutter disk may be effected by a longitudinal displacement of the outer hollow shaft, while the driving shaft may be arranged in fixed bearings so that it can be coupled directly with the motor without using any transmission device.

The accompanying drawing shows, by way of example, an embodiment of the invention. Figure 1 is a longitudinal section through the bark stripping machine and Fig. 2 shows parts of the cutter disk and the protecting disk as seen from the left in Fig. 1.

The cutter disk 1 is fastened by means of threads 2 on a hollow shaft 4 through which the driving shaft 3 is passed. Provided the cutter disk rotates to the right in Fig. 2 said threads are righthanded ones. The protecting disk 5 is fixed to the shaft 3 by means of lefthanded threads 6. The protecting

disk 5 and the cutter disk 1 are connected together by means of pins 7 which are screwed into the protecting disk and enter into axial holes 8 in the cutter disk 1, so that the protecting disk and the cutter disk can be displaced but not turned relatively to each other. The cutters 9, which are fastened to four arms 11 of the cutter disk by means of screw bolts 10, project through openings 12 in the protecting disk. A protecting casing 13 is arranged over the edge of the protecting disk.

The hollow shaft 4 is mounted at one side in an ordinary bearing 14 which allows of an axial displacement of the shaft, and at the other side in a collar-thrust-bearing 15 which in turn is mounted in a fixed frame 16 in such a way that it may be adjusted axially. For the purpose last mentioned the cylindrical body 15 of the bearing engages the frame 16 by means of threads 17 and is provided with a hand wheel 18. By turning the hand wheel the hollow shaft and the cutter disk are displaced longitudinally on the driving shaft. Thus, this arrangement permits of an adjustment of the depths of the cut even during the operation of the machine. The driving shaft 3 is supported partly in the hollow shaft 4, partly by a fixed collar-thrust-bearing. It is driven by means of a pulley 20 but may also be coupled directly to the shaft of the motor. As the shafts 3 and 4 are coupled together by means of the bolts 7, a pulley 21 may be provided on the shaft 4 for driving other machines or apparatus, for instance the trunk forward feed of bark stripping machines.

For the removal of the cutter disk and the protecting disk from their shafts the former is provided with a hole 22 made in one of the arms 11, and the latter provided with a hole 23 said holes being arranged to register with each other, so that a hook 24 of a crane or the like may be introduced through said holes.

The rollers 25 arranged in front of the protecting disk 5 and on which the trunks are carried forward, are rotatably mounted in a standard 26 or the like which normally is screwed to the foundation 27 by means of a nut 28 and, as occasion requires, may be readily unfastened and turned on the shaft 29.

The change of cutters is effected in the following way. After the standard 26 has been turned down and the hook 24 inserted

in the holes 22 and 23 the shafts 3 and 4 are turned simultaneously in opposite directions by means of spanners or levers. The cutter disk 1 and the protecting disk 5 are then, 5 evidently, pushed off their shafts 4 and 3 as a whole so that, finally, they are hanging freely in the hook 24. The disks are then removed and a previously ready made cutter disk with sharp and well balanced cutters 10 together with a protecting disk 5 coupled therewith are brought in position to be screwed on the shafts 3 and 4, which is effected by turning the shafts simultaneously in opposite directions. After having adjusted 15 the depths of the cut by turning the hand wheel 18 the standard 26 is screwed fast in an upright position and the machine is immediately ready for use.

Having now particularly described my invention and in what manner the same is to be performed, I declare that what I claim 20 is:—

1. In bark stripping machines having a cutter disk and a protecting disk mounted 25 one on the shaft of the machine and the other on a hollow shaft arranged concentrically therewith, the arrangement that the cutter disk and the protecting disk are fas-

tened to their corresponding shafts by means of screw-threads running in opposite directions so that said disks may be removed as a whole by turning said shafts simultaneously in opposite directions. 30

2. In bark stripping machines as claimed in claim 1, the arrangement that the outer hollow shaft is rotatably mounted in an axially displaceable collar-thrust-bearing or the like which bearing is mounted in a bearing in a fixed frame and connected to the latter by means of screw-threads, so that the hollow shaft may be displaced axially by turning the collar-thrust-bearing. 35

3. In a bark stripping machine as claimed in claim 1, the arrangement that the parts of the machine which are located in front of the cutter disk and which serve to carry and to guide the trunks, are provided on a swingable frame, so that the cutter disk may be readily removed from the shaft. 40

In testimony whereof I affix my signature 45 in presence of two witnesses.

WILLIAM WAERN.
